UNITED STATES PATENT OFFICE.

HARRY C. CLAY, OF COLUMBUS, INDIANA, ASSIGNOR TO EMERSON-BRANTINGHAM COMPANY, OF ROCKFORD, ILLINOIS, A CORPORATION OF ILLINOIS.

SCARIFIER.

1,155,795.

Specification of Letters Patent.

Patented Oct. 5, 1915.

Application filed September 3, 1914. Serial No. 559,967.

To all whom it may concern:

Be it known that I, HARRY C. CLAY, a citizen of the United States, residing at Columbus, in the county of Bartholomew and State of Indiana, have invented certain new and useful Improvements in Scarifiers, of which the following is a specification.

This invention relates to improvements in scarifying attachments such as are applied to road engines or power road rollers and are used in tearing up old roads by means of teeth which are forced into and through the surface of the road for leveling and subsequent repair of the same.

15 The general object of the invention is to provide a scarifying device which shall be simple in construction, easy to manipulate, and effective and economical in operation.

Heretofore scarifying attachments for 20 road rollers have been known which are characterized by the employment of a toothed-bar suspended from the rear end of the road roller and attached to the latter by pivoted draft bars, with a power cylinder 25 supplied by steam from the boiler of the machine for both raising and lowering the toothed bar and for yieldably holding the latter to its work.

The scarifier of my present invention employs a power cylinder for lowering the toothed bar to working position and for yieldably holding it to its work; but for raising the toothed bar and holding it in elevated or idle position, my invention employs one or more constantly acting springs: and, in its preferred form, the connections between such spring or springs and the toothed bar are such that the initial tension of the spring or springs is just slightly in excess of the power required to hold said parts elevated, and the said connections, during the lowering of the toothed bar, present a continuously decreasing leverage to the spring that is substantially proportional 40 to the continuously increasing tension of the spring as it stretches, so that the lifting effect of the pull of the spring is substantially uniform and constant in all positions of the toothed bar and its suspending means.

Another object of the invention is to provide a new, simplified and improved means for attaching (preferably adjustably) the scarifying teeth to the transverse bar which supports and carries them.

55 Another object is to provide an improved

shoe and means for attaching the same to the toothed bar of the scarifier.

My invention, its mode of operation, and the benefits and advantages attending the same, will be readily understood when considered in connection with the accompanying drawings, in which I have illustrated one practical mechanical embodiment of the invention, and in which—

Figure 1 is a top plan view of the rear end 65 of a road engine showing my improved scarifier applied thereto, the view being partly in horizontal section on the line 1—1 of Fig. 4. Fig. 2 is a detail horizontal section on the line 2—2 of Fig. 5. Fig. 3 is a 70 perspective detail of one of the toothed bar shoes, illustrating the adjustable attachment of the same to the toothed bar, and showing an end fragment of the latter in vertical section. Fig. 4 is a vertical section on the 75 line 4—4 of Fig. 1, and showing the toothed bar and its suspending means in fully elevated position: Fig. 5 is a view similar to Fig. 4, but showing the toothed bar and its suspending means in fully lowered position. 80

Referring to the drawings, 1 designates the boiler, 2 the ground wheels, 3 the axle of the ground wheels journaled in bearings 4 secured to the boiler wing-plates 5, all as usual in road rollers of this type.

85 6 designates a rearwardly extending platform that, with its side walls 7, is secured to the axle bearing 4 and to the boiler wing-plates 5.

8 designates a cylinder that is secured to 90 the underside of the platform 6 and to the axle bearing 4.

9 designates a shaft that is journaled in bearings 10 carried by the side plates 7, on the outer ends of which shaft are fixed arms 11, from the outer ends of which latter depend links 12 that are pivotally connected at their lower ends to a V-shaped transverse bar 13. On the forward face of the bar 13 are cast grooved lugs 14 (Fig. 2) that form 100 seats for the scarifying teeth 15. The lugs 14 are apertured and the front edges of the teeth are notched as shown in 16 to receive U-bolts 17 by which said teeth are strongly and adjustably held on the bar 13. On the 105 ends of the bar 13 are mounted a pair of shoes 18, the shanks 19 of which are channeled as shown in Fig. 3, to receive the ends of the bar 13, this latter being adjustably secured to the shanks of the shoes by bolts 110

29 passing through end flanges 13' of the bar 13 and through any of a series of holes 21 in the shanks of the shoes. The penetrating depth of the teeth 15 can be determined either by adjustment of said teeth on the bar 13 or by adjustment of the bar 13 on the shoes 18, or by both.

On the front face of the bar 13 are a pair of ears 22 (Fig. 2) to which are rigidly secured by bolts 23 a pair of draw bars 24, which latter are pivotally connected at 25 to the wing-plates 5.

Fast on the shaft 9, between the side plates 7, are a pair of crank arms 26, to the outer ends of which are pivoted links 27, the inner ends of said links being connected to the outer ends of a pair of coil springs 28, which latter are anchored at their inner ends to lugs 29 secured to the head of the boiler 1. The constant effort of the springs 28 is to raise and hold raised the scarifying bar and its suspending means; and the initial strength of the springs 28 is slightly in excess of that required for this purpose. By referring to Fig. 4 it will be seen that the springs are acting at the maximum leverage afforded by the crank 26 to rock shaft 9 in a direction to raise the scarifying bar. As the latter is lowered, the leverage of the arms 26 gradually and continuously decreases, and this decrease in leverage is substantially proportional to the gradually increasing tension of the springs, with the result that the lifting energy of the arms 11 is substantially uniform and constant in all of its angular positions. In this connection it may be noted that the purpose of the links 27 is simply to permit the arms 26 to swing downwardly enough to reduce the leverage to the required amount without interference between the springs and shaft 9.

Within the cylinder 8 is a plunger 30 that is connected by a connecting rod 31 to the outer end of a crank arm 32 fast on the shaft 9 between the crank arms 26. The inner end of cylinder 8 communicates with the boiler 1 through a steam supply pipe 33 in which is a three-way valve 34 operated by a handle 35: said valve when turned to one position admitting steam from the boiler to the inner end of the cylinder 8 and when turned to the other position cutting off the boiler and exhausting the steam from the cylinder. The outward movement of the plunger 30 is limited by a plate or ring 36 that is secured to the outer open end of the cylinder 8.

The idle position of the device is illustrated in Fig. 4. When the device is to be put in operation, the valve handle 35 is turned to admit steam to the cylinder 8, whereupon the parts at once assume the working position substantially as shown in Fig. 5, during which movement the springs

28 are stretched but without imposing any increasing back drag on the shaft 9 by reason of the decreasing leverage of the arms 26 already referred to. While the machine is in operation the steam power on the piston 30 acts as a cushion to permit the scarifying bar to yield upwardly in the event of meeting a hard and unyielding obstacle such as would be likely to break the teeth. When the operation is finished, the valve 75 handle is turned in the opposite direction to open the cylinder 8 to the exhaust, and the springs 28 at once return the scarifying bar and its suspending parts to the elevated or idle position shown in Fig. 4. It will 80 thus be evident that the fluid pressure is used only to overcome the slight resistance of the springs 28 in lowering the device on to the ground and to hold the teeth into the surface of the road, while the spring 85 force is used in holding the device up automatically from the road, being always ready to perform its function whether the fluid pressure is on or off. This arrangement makes possible the use of a trunk piston or plunger which eliminates the use of a stuffing box and also cross-head and guides to resist the angular thrust of the connecting rod. While the work is in progress the scarifying bar frequently has to be 90 held up from the surface of the road as well as on the surface of the road, and since the fluid pressure is used on one side only of the piston, there is less of the fluid used, as compared with double-acting cylinders, notwithstanding the piston has to have a little excess area to overcome the spring force in addition to performing the work of forcing the teeth into the road, which spring force is a small item in comparison with the pressure exerted on the teeth by the plunger.

While I have described what I regard as a preferred embodiment of the invention, it will be manifest to those skilled in the art 110 that this embodiment may be changed and modified more or less in detail without involving any departure from the principle of the invention or sacrificing any of the advantages thereof. Hence I do not limit 115 the invention to the particular form shown and described, except to the extent clearly indicated in specific claims.

I claim—

1. The combination with a road engine, 120 of a scarifying attachment therefor comprising a toothed member suspended transversely beneath the rear of said engine, draw bars secured to said toothed member and pivotally connected to said engine, a 125 spring for raising said toothed member and its suspending means, connections between said spring and said toothed member affording a decreasing leverage for the spring as the latter is stretched in lowering the 130

toothed member onto the ground, and fluid pressure operated means for holding said toothed member on the ground in opposition to the action of said spring.

6. 2. The combination with a road engine of a scarifying attachment therefor comprising a toothed member suspended transversely beneath the rear of said engine, draw bars secured to said toothed member and pivotally connected to said engine, a spring for raising said toothed member and its suspending means, connections between said spring and said toothed member affording a decreasing leverage for the spring that is substantially proportional to its increasing tension as it is stretched in lowering the toothed member onto the ground, said spring having an initial tension but slightly in excess of that required to hold said toothed member and its suspending means in raised position, and fluid pressure operated means for holding said toothed member on the ground in opposition to the action of said spring.
10. 3. The combination with a road engine, of a sacrificing attachment therefor comprising a toothed bar located transversely beneath the rear of said engine, draw bars secured to said toothed bar and pivotally connected to said engine, a rock-shaft journaled above and parallel with said toothed bar, rearwardly extending arms on said rock-shaft, links connecting said arms with said toothed bar, a crank-arm on said rock-shaft, a single-acting power cylinder having a plunger connected to said crank-arm and acting to lower said toothed bar onto, and hold it engaged with, the ground, a tension spring anchored at one end to said engine, and connections between the other end of said spring and said rock-shaft such that said spring opposes, with a substantially constant turning movement, the turning movement of said rock-shaft in a direction to lower said toothed bar onto the ground.
15. 4. The combination with a road engine of a scarifying attachment therefor comprising a toothed bar located transversely beneath the rear of said engine, draw bars secured to said toothed bar and pivotally connected to said engine, a rock-shaft journaled above and parallel with said toothed bar, rearwardly extending arms on said rock-shaft, links connecting said arms with said toothed bar, a crank-arm on said rock-shaft, a single-acting power cylinder having a plunger connected to said crank-arm and acting to lower said toothed bar onto, and hold it engaged with, the ground, a tension spring anchored at one end to said engine, and connections between the other end of said spring and said rock-shaft such that said spring opposes, with a substantially constant turning movement, the turning movement of said rock-shaft in a direction to lower said toothed bar onto the ground.
20. 5. The combination with a road engine, of a sacrificing attachment therefor comprising a toothed bar located transversely beneath the rear of said engine, draw bars secured to said toothed bar and pivotally connected to said engine, a rock-shaft journaled above and parallel with said toothed bar, rearwardly extending arms on said rock-shaft, links connecting said arms with said toothed bar, a crank-arm on said rock-shaft, a single-acting power cylinder having a plunger connected to said crank-arm and acting to lower said toothed bar onto, and hold it engaged with, the ground, a tension spring anchored at one end to said engine, and connections between the other end of said spring and said rock-shaft such that said spring opposes, with a substantially constant turning movement, the turning movement of said rock-shaft in a direction to lower said toothed bar onto the ground.
25. 6. The combination with a road engine, of a sacrificing attachment therefor comprising a toothed bar located transversely beneath the rear of said engine, draw bars secured to said toothed bar and pivotally connected to said engine, a rock-shaft journaled above and parallel with said toothed bar, rearwardly extending arms on said rock-shaft, links connecting said arms with said toothed bar, a crank-arm on said rock-shaft, a single-acting power cylinder having a plunger connected to said crank-arm and acting to lower said toothed bar onto, and hold it engaged with, the ground, a tension spring anchored at one end to said engine, and connections between the other end of said spring and said rock-shaft such that said spring opposes, with a substantially constant turning movement, the turning movement of said rock-shaft in a direction to lower said toothed bar onto the ground.

LAFE BRUCE,
ALBERT T. CLAY.

It is hereby certified that in Letters Patent No. 1,155,795, granted October 5, 1915, upon the application of Harry C. Clay, of Columbus, Indiana, for an improvement in "Scarifiers," errors appear in the printed specification requiring correction as follows: Page 3, claim 2, strike out line 19; same page, line 27, claim 3, for the word "sacrificing" read *scarifying*; and that the said Letters Patent should be read with these corrections therein that the same may conform to the record of the case in the Patent Office.

Signed and sealed this 2nd day of November, A. D., 1915.

[SEAL.]

R. F. WHITEHEAD,
Acting Commissioner of Patents.
